UNITED STATES PATENT OFFICE.

CHARLES B. WEBSTER, OF FALL RIVER, MASSACHUSETTS, ASSIGNOR TO JAMES K. LANNING, OF BOSTON, MASSACHUSETTS.

WINDING MECHANISM.

1,141,890.

Specification of Letters Patent.

Patented June 1, 1915.

Application filed May 28, 1913. Serial No. 770,425.

To all whom it may concern:

Be it known that I, CHARLES B. WEBSTER, a citizen of the United States, and resident of Fall River, in the county of Bristol and 5 State of Massachusetts, have invented an Improvement in Winding Mechanism, of which the following description, in connection with the accompanying drawings, is a specification, like characters on the drawings 10 representing like parts.

This invention relates to winding mechanism for forming yarn or thread packages and specifically and more particularly to builder mechanism for ring spinning or 15 twisting mechanism.

The present invention is intended to present a simple form of single acting traverse and gain controlling mechanism, to which existing mechanisms may be readily adapted 20 and in the illustrated embodiment I have shown the same as involving the take-up of the flexible element although, obviously, by a suitable re-arrangement of parts the mechanism is equally well adapted to the let- 25 off of the flexible element.

In order that the principle of the invention may readily be understood, I have chosen to illustrate that embodiment thereof consisting of builder mechanism for ring 30 spinning frames,—that is, a specific application of winding mechanism.

In the drawings: Figure 1 is a front elevation of one form of builder mechanism for ring spinning frames constituting an embodiment of the invention; Fig. 2 is a view of said mechanism partially in vertical transverse section and partially in end elevation; Fig. 3 is a view in side elevation of a portion of the mechanism shown in Fig. 1, 35 upon an enlarged scale; Fig. 4 is a detail, partially in section and partially in side elevation of a portion of the mechanism shown in Fig. 3; Fig. 5 is a detail in side elevation of one of the series of interchangeable 40 sheaves; Fig. 6 is a longitudinal section taken upon the line 6—6 of Fig. 3; Fig. 7 is a longitudinal vertical section taken through one of the shafts of the mechanism; and Fig. 8 is a detail showing the preferred 45 manner of detachably supporting the sheaves in position.

In yarn or thread winding mechanism to which my invention relates, the coils of yarn are laid along the yarn receiver by effecting a relatively oscillatory movement of a yarn 55 guide and the yarn receiver along the latter for a portion of its length, which movement is generally called the "traverse"; and the package is built by shifting the path of this relative movement progressively along the 60 axis of the yarn receiver, which shifting is usually termed the "gain." In the formation of such a yarn package, a maximum diameter is reached at a point above the lower end thereof due to the cooperative ef- 65 fect of the traverse and the gain; and the portion of a package from its lower end to such point of maximum diameter is termed the "base"; while the conical form resulting at the other end of the yarn package is 70 termed the "chase," or the "taper"; and its terminus is the "nose" of the cop.

My invention provides means whereby the package may be wound or formed with efficiency in a winding or spinning or twisting 75 machine; and particularly in a spinning or twisting machine it furnishes means whereby the tension of the yarn in winding may be well controlled and the lay of the yarn thereby benefited.

In the formation of the base of the package, the invention provides means whereby the successive layers of yarns may be so laid, one over the other, until the full diameter of the package is secured, that each 85 bottom coil of each layer is laid safely up and above the bottom coil of the preceding layer, (assuming the yarn receiver to be upright and the yarn to be wound thereon from the bottom upward, as in the preferred 90 arrangement of parts of mechanism embodying my invention); and while the mechanism accomplishes this broadly in the formation of the base of a package, it may be arranged to continue the same winding 95 effect throughout the entire length of the package. This feature of the winding is accomplished by providing a gain which may be of any suitable character and which preferably increases, progressively or otherwise, throughout the whole of the base of 100 the package at least. Throughout the re-

mainder of the package, the gain should be such as to maintain the body of the package substantially uniform in diameter. To this end I may, while constantly increasing the 5 traverse throughout the cop, so control the gain as to accomplish this result. This may be effected by providing for an unincreased gain throughout the body of the package above the base, provided the increasing 10 traverse be maintained. Coöperatively with this mechanism for increasing the gain, mechanism is provided to increase the traverse throughout the formation of the base and preferably throughout the formation of 15 the whole package. The result of this increase of traverse is obviously to lay each successive layer of yarn over a slightly greater extent axially of the package; and further, due to the constant speed of the 20 spindle or other yarn receiver, and in ring frames particularly, due further to the constant speed of the feed rolls, if each traverse is effected in the same period of time (which is accomplished by giving the primary controller 25 of the traverse movement a stroke constant in time and distance), the yarn will each time be laid in coils a little more widely separated. Having reference to the utilization of such a yarn package which involves 30 its unwinding features, the result is that the increasing traverse from base to nose gives a reversely decreasing taper from nose to base, so that the yarn withdrawn by draft axially of the package is drawn from 35 a surface on the package approaching more and more nearly to a surface at right angles to the axis of the package. By this means, as the length of yarn extending from the surface wherefrom it is being delivered to 40 the point above the package where draft is being applied to the yarn tends to increase, and ballooning of the yarn away from the package tends to increase, this tendency to increase the ballooning effect is checked by 45 the yarn drawing from a surface tending to approach more and more nearly to a flat surface at right angles to the package; and when the yarn package is positioned in the shuttle this described construction of package 50 checks the tendency of the yarn to balloon out and contact with the sides of the shuttle and therefore, tends to decrease breakage. Furthermore, as the base of the cop is reached in the unwinding (and 55 throughout the whole package, if and when the increase in gain is established through the whole package) each bottom coil of each layer (having been safely laid by means of the increase in gain over and above the bottom 60 coil of the preceding layer) is permitted to be withdrawn without fouling with and tending to slough off the preceding layer. These advantages thus secured in the unwinding are of great practical importance

in weaving where the yarn is subjected to 65 quick intermittent draft reaching a speed of from five to ten yards a second.

A yarn spinning frame constructed in accordance with my invention is provided with a ring rail and continuously rotating 70 yarn receivers, herein represented as spinning spindles having bobbins of paper or similar tubes thereon. Within the scope of my invention, the yarn may obviously be spun or wound upon the bare spindles. The 75 travelers or the rings and the travelers constitute the yarn guiding means and the ring rail or the ring rail and poker constitute a yarn guiding holding means, and I cause a relative to and fro traversing movement between 80 said yarn guiding means and said yarn receivers. Preferably this is effected by imparting the described traversing movement to the ring rail.

Inasmuch as each traverse is increased 85 over its predecessor, each traverse advances more at the top of the wind than at the bottom thereof. The effect of the described traverse and gain are to build a yarn package which at the bottom extends from the 90 surface of the receiver to a maximum diameter without laying the bottom coil of any wind or traverse on top of or below the bottom coil of the preceding layer or traverse. The slight but continuous incremental 95 increase in the gain throughout at least the base of the package, together with the direct increase of the traverse, lays the yarn so uniformly that the chase of the yarn package is formed with a straight line constituting 100 a conical bottom in vertical cross section, until the maximum diameter of the cop or other yarn package is reached. Thus, the increase in traverse and incremental increase in gain are effective to produce and maintain 105 a correct and advantageous form of package. While I have referred to the increase in the traverse as constant, this term is employed generically or broadly to refer to a preferably regular increase in the traverse, 110 such increase occurring at a certain part of the traverse, or if desired, at a certain part of each of a series of traverses. I preferably impart the increase to the traverse and the increase to the gain during the up-stroke of the ring rail, and preferably near the end of such up-stroke and terminating with the end of the up-stroke.

Inasmuch as the builder cam employed in the disclosed embodiment of the invention 120 rotates preferably at a constant speed, and inasmuch as the traverse is regularly increased, it follows that the speed of the ring rail is correspondingly increased, and inasmuch as the addition to the traverse and the 125 addition to the gain are imparted in the present embodiment at or near the end of the up-stroke of the ring rail, it follows that

the speed of the movement of the ring rail is accelerated each time toward the end of its up-stroke,—that is, when the yarn is winding upon the nose of the yarn package.

5 An important object of my invention is the provision of suitable means whereby the traverse and also the gain may be changed independently of each other, and whereby if either the traverse or the gain be varied, 10 suitable compensation may be made to prevent variation of the other factor, if desired. In this manner, bobbins may be wound which are of different lengths, but wherein the traverse is correspondingly the same, 15 and wherein the total gain varies. Any other desired change in the factors entering into the winding of the bobbin may be made.

Referring more particularly to the drawings, the builder element herein shown is a 20 cam, as indicated at 2 in Fig. 1, it being fast upon a shaft 1, supported upon the framing and driven preferably at a constant speed in the direction of the arrow thereon, from any suitable mechanism, such for example 25 as a worm shaft which is itself driven by sprocket gearing or otherwise, from the main drive shaft of the spinning frame. I am enabled, because of my invention, to drive the shaft 1 and its cam 2 at a higher 30 rate of speed than heretofore without changing the speed at which the drawing or feed rolls or spindles are driven, and therefore to impart more rapid traverses to the ring rail without, however, changing the speed of 35 the spindles which are preferably driven by bands from the drum, and hence independently of the ring rail.

While I may employ any suitable contour or type of builder element, I have herein represented the builder cam as adapted to make 40 but a partial revolution for each complete traverse of the ring rail.

The spindle rail is represented at 3, the spindles at 4, the ring rail at 5, the spinning rings at 6, and the box rail or frame of the spinning frame at 7. These parts may be 45 and preferably are of usual formation and construction, the spindles being continuously rotated in one direction, preferably by bands from the usual drum and the yarn being 50 delivered thereto by the usual sets of drawing rolls, not shown.

Suitably mounted in the frame of the machine, upon a stud or pivot 8 is a builder 55 lever 9 preferably having a member 10 relatively adjustable with respect thereto by a set screw or otherwise, as indicated at 11, and having a roll 12 engaging the periphery of the builder element 2. It will be observed 60 that the builder lever 9—10 is mounted to rock in a plane extending longitudinally of the frame, and this construction is preferably employed wherein the parts operate by take-up of the flexible element. I may, how-

ever, employ a lever mounted to swing in a 65 plane transverse to the frame, and particularly if the parts operate by let-off of the flexible element as may be readily effected within the scope and object of my invention.

Suitably mounted in the frame of the machine and as herein shown, in a bracket 13, is a bell crank lever 14 having an arm 15 upon which rides the lower end of the poker arm or rod 16 depending from the ring rail 5. The lever 14 is provided with an upward 70 extension 17 to the other end of which is suitably secured one end of a flexible connection herein shown as consisting of a pair of chains 18. These chains are arranged in pairs throughout the frame and a suitable 75 number of sprocket chains and bell crank levers and poker arms or rods are provided to impart a steady up and down movement to the ring rail 5, and preferably a ring rail and a row of spindles are arranged at each 80 side of the spinning frame.

In building the yarn package, the yarn is laid upon the receiver in a series of nested cones, each of which is formed during a 85 traverse of the ring rail. In order that these 90 traverses may extend along or with suitable relation to the receiver, an incremental gain of any suitable character is imparted to the 95 traversing mechanism preferably between the successive traverses throughout at least 100 the base of the package, during the winding of which the gain is preferably a progressively increasing one. In the present embodiment of the invention, both the traverse and the gain are effected through the chain 105 or other flexible connection or connections 110 18. Herein, each chain 18 is represented as attached fixedly at one end to the arm 17 of the lever 14 and at the other end is connected as hereinafter described to a governing device carried by the builder lever 9—10.

The longitudinal pull imparted to the chain or chains 18 by the builder element 2 rocks the bell crank lever 14 through arcs, the angular extent and position whereof are modified, as hereinafter set forth, by mechanism acting upon said chains 18 between the ends thereof, to effect the laying of the yarn by traverses which are maintained undiminished and preferably have a regular uniform increase and by a gain which is also maintained undiminished and which preferably 115 progressively increases throughout at least 120 the base of the package.

In order to secure a traverse and a gain of 125 the character above indicated and which may be varied as desired, I have provided adjunctive means coöoperating with the builder lever and connections therefrom such that the invention may be readily applied to existing types of ring spinning frames, (inasmuch as an important object of the invention is to provide mechanism of

an exceedingly simple character for the purpose stated) and which may be adapted to existing types of ring spinning and other winding frames with comparatively little change. Herein for the purpose, I have mounted upon the box rail 7 a bracket 19 indicated most clearly in Fig. 2, and upon the upper end thereof have mounted upon a pivot or stud 20 a lever 21 having at its lower end a toothed segment 22 meshing with a gear 23 having a hub 20' loose upon the shaft 24, that is mounted in an upward extension 25 of the builder lever 9—10.

As shown most clearly in Fig. 7 the gear 23 is provided with a hub 26 extending through the bracket 19 (which is suitably recessed to permit the described rocking of the builder lever 9—10 and the parts carried thereby), and fast upon said hub 26 is a disk 27 carrying a pawl 28 adapted to engage the teeth of a ratchet 29 shown most clearly in Fig. 3 and which is fixed upon the shaft 24. The said ratchet 29 is adapted, when intermittently actuated by the pawl 28, to impart a step by step rotation to the shaft 24. The upward extension 25 is provided with a sleeve 30 wherein the shaft 24 is mounted and upon the end of the sleeve 30 adjacent the disk 27 is mounted a casing 31 partially surrounding the ratchet 29, as indicated in Fig. 3, and providing means whereby the pawl 28 engages the ratchet at or near the end of each movement or oscillation of the segment 22. The casing 31 is provided with a hub 32 which is fitted on to the sleeve 30 and provided with a set screw 33 for securing it thereon in fixed position, but permitting circumferential adjustment of the shield, thereby to vary the extent of the pick. It will be observed that with the pick mechanism as above shown, a pick takes place when the ring rail is completing the up portion of its traverse although within the scope of the invention the pick may take place while the ring rail is completing the last portion of its down traverse or at such other time as may be suitable.

Since the pick mechanism in the present embodiment of the invention effects both traverse and gain it results that not only is the incremental increase in gain, of whatever character, added just at the time when the ring rail is completing the up portion of its traverse, but also, since the increase in the traverse increases the general speed of the ring rail during the traverse, it follows that the traverse is speeded up just as the ring rail is completing its up-stroke. These two factors coöperate in the operation of the mechanism to secure the proper laying of the yarn by tending, first, to keep the coils of each traverse laid well above each other at the top, and second, to reduce the number of coils laid at the top,—that is,

when the yarn is being wound upon that portion of the coil that is of the smallest diameter and hence when yarn breakage is most apt to occur. The number of coils laid at the top portion of each traverse is reduced in the manner described inasmuch as the number of coils laid at any portion of the yarn package varies inversely as the speed of the ring rail traversing each portion of the package.

The described increase in the speed of the ring rail at the upper portion of each traverse not only tends to compensate for the inherent tendency of the spinning mechanism to lay more winds of yarn at the upper portion of its traverse, but it also tends to compensate for the lag of the traveler at the upper portion of the up-stroke of the ring rail and therefore results in less variation of the speed of the traveler due to this lag at the up portion of its stroke; and not only tends to reduce causes effecting the yarn breakage but tends to produce a yarn package wound with more uniform tension throughout.

The lever 21 carrying segment 22 may be oscillated in any suitable manner, but preferably by movement of the builder lever 9—10. Herein for the purpose, I have provided the builder lever with the arm 25 as hereinbefore described (or I may mount such arm upon the rock shaft 8 co-axially with the builder lever 9—10). At its upper end the arm 25 is provided with a lateral extension 34 having a transverse slot 35. The lever 21 extends upwardly beyond its pivot 20 as indicated in Figs. 2 and 3, and is there provided with an open slot 36 receiving a bolt 37 extending through the lever 21 and the slotted extension 34. The provision of the transverse slot 35 permits variation in the relation of the segment 22 and the gear 23.

Vertically mounted in the arm 25 is a threaded shaft or screw 38 shown most clearly in Fig. 4 and fast upon the lower end thereof is a beveled gear 39 meshing with the beveled gear 40 that is fast upon the shaft 24. The shaft or screw 38 is readily removable and may be replaced by one having a coarser or a finer thread, in lieu of varying the pick. In either manner the traverse may be varied but preferably I accomplish this result by varying the pick. Held from turning upon the screw 38 is a nut 41 which at the commencement of the building of the cop is at or near the lower end of the screw 38 and is gradually elevated by the rotation of the screw from the shaft 24.

The nut 41 has loosely mounted therein the stud shaft 42 extending through and projecting at both sides from said nut. Keyed at 42' upon the ends of the said stud

shaft 42 so as to be readily and independently removable are two sheaves 43-44 shown most clearly in Fig. 2. These sheaves are herein represented as truly circular but 5 may be formed as scroll cams, or of any other desired form to effect the take-on or let-off of the chain in any desired manner.

The ends of the flexible elements or chains 10 18 are fixedly attached to the periphery of the said sheaves by bolts or otherwise as indicated at 45 in Figs. 1 and 3.

The sheaves 43-44 may be secured to the stud shaft 42 in any suitable manner permitting ready removal thereof so that other 15 sheaves of greater or less diameter may be substituted therefor. Within the scope of my invention, I may provide a series of expandable sheaves or like devices so that the diameter thereof may be increased or diminished and also within the scope of my 20 invention I may provide the shaft 42 with an additional set or sets of sheaves so that the chains may be shifted from the sheaves of one set to those of another of different 25 diameter upon suitable change in the position of the parts. Thus, in any suitable way I provide for varying the effective diameter of the sheaves. The described result is most simply secured by providing a series of interchangeable sheaves of different diameters, 30 any desired number of which may be employed.

As heretofore pointed out, by changing the pick (that is, by varying the number of 35 teeth by which the ratchet 29 is advanced at each pick) or by changing the pitch of the screw 38, I change the traverse, inasmuch as the traverse is determined by the total outward movement of the builder nut 40 41. The length of the bobbin or yarn package represents the total gain and it is, therefore, evident that if the pick be lessened, thereby lessening the traverse, and there is no compensating change governing or 45 compensatingly increasing the gain, too short a bobbin or yarn package would be secured. Inasmuch as the outward movement of the nut, (which is controlled by the pick) represents and effects the traverse, and inasmuch as rotation of the sheaves 43-44 50 represents and effects the gain, I therefore provide means, of which I have disclosed one embodiment, whereby I may change the traverse, and may, if desired, compensatingly change the gain. If no provisions 55 existed for compensatingly changing the gain upon variation of the traverse, then a change in the traverse would necessarily modify the gain, so that in many cases the 60 result would be too short a yarn package. In accordance with my invention, however, I may change either the traverse or the gain independently of each other. If, therefore, I wish to change one of the factors, as for

example the traverse, without changing the other factor, as for example the gain, then after changing the traverse I make a change in the gain to compensate for the change in the traverse, so that the resulting gain is the same as it would have been had the traverse not been altered. Furthermore, within the scope of my invention, I may change both the traverse and the gain either compensatingly or otherwise and within the scope of my invention the gain may be of any suitable character. If, for example, the sheaves 43-44 be formed as scrolls, then a progressively increasing gain results. It will thus be evident that with the same outward movement of the builder nut I may 80 take on (or let off) less chain by making the sheaves 43-44 smaller or by making larger the remaining sheave of the series to be described. Conversely, if, with the same total outward movement of the builder nut, I wish 85 to take on (or let off) more chain, then I employ larger sheaves 43-44 or a smaller final sheave of the series. Furthermore, within the scope of my invention, in different total movements of the builder nut 41 I may 90 take on (or let off) a fixed amount of the chains 18. Thus I have provided means whereby in different cases, more or less increase in the traverse may be had as desired, with any desired let-off or take-on of the 95 flexible elements 18. To this end I have, in Fig. 5, shown one of a pair of sheaves 46 which is of a slightly larger diameter than the sheaves 43-44. When a pair of sheaves 46 is substituted for the sheaves 43-44, it 100 is evident that a greater amount of chain is taken on with the same total movement of the builder nut. It is also evident that if the mechanism be employed to let off the flexible element or elements instead of to 105 take on the same, that the sheaves 46 will in such case let off a greater amount thereof for the same total movement of the builder nut. If it be desired to operate by let-off, I may, as previously stated at the outset of the 110 specification, effect this by a suitable rearrangement of the parts. Referring to the illustrated form of the invention, if it be desired to operate by let-off, the chain 18 may extend directly to the under side of the 115 sheaves 43, 44 and be suitably connected to said sheaves instead of extending to the upper side thereof, as herein shown, wherein mechanism operating by take-up is illustrated. It is, therefore, evident that by 120 the described mechanism I have provided means whereby, if desired, the amount of increase in the traverse may be varied. It is evident that other suitable mechanism may be provided for the same purpose. I 125 have also provided suitable means for varying the increment of gain and for varying the total gain, such means for varying the

increment of gain being independent of the means for varying the amount of increase in the traverse.

As shown most clearly in Figs. 2, 3 and 8 I also key at 42' upon the stud shaft 42, and in this instance adjacent the sheave 44, a sheave 47 of suitable diameter and having secured to the periphery thereof at a suitable point, as by means of a bolt, a flexible element or chain 48, the other end whereof is fixedly secured at 49 to the builder lever 9-10, as most clearly indicated in Figs. 1 and 3. The sheave 47 constitutes the final sheave of the series used at any one time and may be readily replaced by other sheaves of greater or smaller diameters. I have herein represented the sheave 47 as of greater diameter than the sheaves 43-44 but it will be understood that in such case any given arc of movement of the sheave 47 will result in the taking on of a less length of chain 18 on to the sheaves 43-44 than would be the case if the sheave 47 were of relatively smaller diameter. The chain 48, connected as it is to the sheave 47, and to the builder lever 9-10, compels a slow rotation of the sheaves 43-44 in the direction of the arrow in Figs. 3 and 4 during the outward travel of the nut 41 from the fulcrum of the builder lever 9-10. The sheave 47 may be of any suitable diameter and as stated, may be varied as desired by the provision of interchangeable sheaves or in any other manner referred to in connection with the sheaves 43-44, so that any desired character of gain in the yarn package may be secured. Preferably the character of the sheaves is such that throughout at least the base of the yarn package a progressively increasing gain is imparted though, as previously stated, within the scope of my invention, any other desired character of gain may be imparted as for example, a progressively decreasing or other decreasing character of gain. Preferably, however, the construction is such as to maintain the gain undiminished throughout at least the winding of the base of the package. If it be desired, as already discussed, to operate the mechanism by let-off, in which case the chains 18 may, as previously stated, extend directly to the under side of the sheaves 43, 44, the chain 48 should also be reversed or rearranged, and may extend from the under side of the sheave 47 to a suitable point of attachment upon the upright arm of the builder lever above said sheaves. In other forms of builder arms or levers, suitable rearrangement may be made to effect change from take-up to let-off, or vice versa. The gradual elevation of the nut 37 and the consequent change in position of the chains 18 effect a constant increase in the traverse. As herein represented, the pick mechanism is con-

stant or unvarying in operation and the movements of the nut 41 upon the screw 38 are uniform.

The described movements of the parts are such as to effect an increase in the gain throughout at least the base of the package and it will be observed that the distance between the point of attachment of the chains 18 to the arm 17 of the bell crank lever and the sheaves 43-44, measured along the shortest line, is incrementally lessened. Moreover, inasmuch as when the ring rail 5 is in its lowermost position, the arm 15 of the bell crank lever is somewhat below and is moving toward the horizontal, it follows that the linear movements imparted by the arm 15 to the poker arm or rod 16, gradually increase in length due to the movement of said arm upwardly toward the horizontal in analogy to the increased linear movements imparted by a crank when approaching the horizontal. Such increased linear movements of the poker arm or rod 16 continue throughout the formation of the base of the package, at least.

In the present embodiment of the invention the elements combine to effect an increasing gain throughout the formation of the base of the package and the continued movement of the arm 15 is not thereafter such as substantially to modify the character of the gain during the further formation of the yarn package.

It will be evident from the foregoing that the invention is readily adapted for use in connection with mechanism operating either by take-up or by let-off of the flexible element, it being herein shown as operating by take-up. Any desired total increase of traverse can be had, as previously stated, by properly regulating the pick mechanism and the screw 38 controlling the builder nut. With any total increase of traverse, any desired total increase of gain can be had. Thus an increase of total traverse can be had in the same movement of the builder nut by increasing the diameter of the disks 43, 44, to which the chains 18 are connected, or by decreasing the diameter of the disk 47 to which the chain 48 is attached. Conversely a decrease of total gain can be had by decreasing the diameter of the disks 43, 44, or by increasing the diameter of the disk 47. Finally the rate of variation of the gain can be controlled by properly varying the form of the disks 43, 44, and if desired of disk 47, as by making them of scroll form, as hereinbefore set forth. It will thus be seen that the mechanism has a maximum capacity for adjustment. It is thus possible to change the total length of the cop or yarn package and a given amount of increase of the traverse can be retained, as also any desired variation of the gain.

Although I have referred to the increase in the traverse as constant, it will be understood thereby is meant a regular or periodic increase inasmuch as in practice the traverse is not increased at all instants of time during the operation of the mechanism, but preferably at a certain period of time or part of each traverse.

After the nut 41 has been elevated by rotation of the screw 38 in the building of the yarn package, the said nut is returned, preferably by hand, for the formation of the next set of yarn packages. Herein for the purpose, I have provided the shaft 24 with a crank handle 50 shown in Figs. 1 and 3, so that by rotation of said shaft and of the screw 38, the nut 41 may be lowered to the desired extent.

It will be understood from the foregoing description that the effect of the travel of the nut 41 upon the chains 18 is such that the arcs of movement of the bell crank lever 14 not only gradually increase in length, providing the gradually increasing length of conical layers, but the said arcs of movement are gradually increased contra-clockwise so that the rods or poker arms 16 descend to an incrementally higher point after each upward operation of the traverse, thus providing a gain which, as previously stated, is increased.

In employing the term "traverse" I mean a complete forward and return movement of the yarn guide or complete relative forward and return movement of the same with respect to the yarn receiver. Each return movement of the traverse terminates at a distance above the commencement of the traverse measured by the extent of the gain.

As previously stated, the disclosed embodiment of the invention provides means for controlling the gain and traverse in a form wherein the flexible element is progressively shortened or taken on. Modification of the mechanism to give the same control, *i. e.*, increasing traverse as discussed, and generally decreasing gain as discussed is readily secured by so arranging the outwardly moving builder nut and scroll that the flexible element is released by increasing increments as the builder nut moves outward by uniform increments; being essentially the reverse of the arrangement herein shown. Furthermore the application of the said traverse and gain controlling mechanism to builder mechanism wherein the flexible element is let off or elongated during the winding operation, will be readily apparent to those skilled in the art. Thus, either a take-on or let-off form of mechanism may be provided.

Another advantage of the described wind is that I so regulate the decrease in the speed in the winding on of the yarn upon

the portion of the yarn receiver that is of least diameter (and by such diameter I mean the least diameter of that portion of the yarn receiver covered by each traverse of the yarn) that the lag of the traveler as the ring rail moves toward and away from the ends of the yarn package is minimized. Therefore, a more generally rapid movement of the ring rail per minute may be effected, so that with an assumed spindle speed and an assumed ring rail speed, a more open lay of the wind may be accomplished. I have previously stated that the lag of the traveler is diminished by increasing the ring rail speed inasmuch as fewer turns of the yarn are laid at the upper end of each traverse. It will be evident that by laying the yarn as an open wind, the number of turns is further lessened, thus still further minimizing the lag of the traveler.

As a specific instance of the capacity of the described mechanism, I may state that it is possible to get an increase in the traverse from a starting traverse of say three quarters of an inch to an ending traverse of one and one eighth inches and simultaneously to take on five inches of the chains 18. It may, however, be desired to get an increase in the traverse from a starting traverse of three quarters of an inch to an ending traverse of one and one half inches and at the same time not take on more than the said five inches of chain. Any other suitable manipulation may be effected. It will, therefore, be understood that by avoiding the taking on of a greater amount of chain, I avoid the lifting of the ring rail too high and the winding of a too long bobbin.

Having thus described one illustrative embodiment of my invention, I desire it to be understood that although specific terms are employed, they are used in a generic and descriptive sense and not for purposes of limitation, the scope of the invention being set forth in the following claims.

Claims:

1. Winding mechanism for forming packages comprising in combination with a rotating yarn receiver and a yarn guide traversable lengthwise thereof, a traverse and gain controlling mechanism for the guide; said mechanism embodying an actuator lever having a to and fro stroke, yarn guide holding means and coöperating connecting and governing devices on said lever and between the same and said holding means; said devices comprising a flexible element adapted to move to and fro with said lever, and governing means on said lever active on said flexible element and to which the latter is connected, to move the point of engagement thereof with said flexible element gradually and incrementally.

outward from the fulcrum of said lever, thereby gradually to increase the traverse, said governing means including a rotatable member, means to move the same, and a second flexible element operatively connected to said member and also to the actuator lever; the said connecting and governing devices further comprising a second oscillatory pivoted member positively connected to said first flexible element and having coöperative relation with said yarn guide holding means.

2. Winding mechanism for forming packages comprising in combination with a rotating yarn receiver and a yarn guide traversable lengthwise thereof, a traverse and gain controlling mechanism for the guide; said mechanism embodying an actuator lever having a to and fro stroke, yarn guide holding means, and coöperating connecting and governing devices on said lever and between the same and said holding means; said devices comprising a flexible element adapted to move to and fro with said lever, and governing means on said lever active on said flexible element and to which the latter is connected, to move the point of engagement thereof with said flexible element gradually and incrementally outward from the fulcrum of said lever, thereby gradually to increase the traverse, said governing means including a rotatable member, means to move the same outward from the axis of the actuator lever; and a second flexible element operatively connected to the said rotatable member and also to the actuator lever; the said connecting and governing devices further comprising a second oscillatory pivoted member positively connected to said first flexible element and having coöperative relation with said yarn guide holding means.

3. Winding mechanism for forming packages comprising in combination with a rotating yarn receiver and a yarn guide traversable lengthwise thereof, a traverse and gain controlling mechanism for the guide; said mechanism embodying an actuator lever having a to and fro stroke, yarn guide holding means and coöperating connecting and governing devices on said lever and between the same and said holding means; said devices comprising a flexible element adapted to move to and fro with said lever, and governing means on said lever active on said flexible element and to which the latter is connected, to move the point of engagement thereof with said flexible element gradually and incrementally outward from the fulcrum of said lever, thereby gradually to increase the traverse, said governing means including a rotatable sheave, means to move said nut outward from the fulcrum of the lever, and a second flexible element operatively connected to said sheave and to said actuator lever, the said connecting and governing devices further comprising a member positively connected to said first flexible element and having coöperative relation with said yarn guide holding means.

sheave and also to said actuator lever, the 65 said connecting and governing devices further comprising a second oscillatory, pivoted member positively connected to said first mentioned flexible element and having coöperative relation with said yarn guide 70 holding means.

4. Winding mechanism for forming packages comprising in combination with a rotating yarn receiver and a yarn guide traversable lengthwise thereof, a traverse 75 and gain controlling mechanism for the guide; said mechanism embodying an actuator lever having a to and fro stroke, yarn guide holding means and coöperating connecting and governing devices on said lever 80 and between the same and said holding means; said devices comprising a flexible element adapted to move to and fro with said lever, and governing means on said lever active on said flexible element to move 85 the point of engagement thereof with said flexible element gradually and incrementally outward from the fulcrum of said lever, thereby gradually to increase the traverse, said governing means including a nut having 90 a rotatable sheave, means to move said nut outward from the fulcrum of the lever; a second flexible element operatively connected to said sheave and to said actuator lever, said connecting and governing devices further comprising a second, oscillatory, pivoted member positively connected to said first mentioned flexible element and having coöperative relation with said yarn 95 guide holding means.

5. Winding mechanism for forming packages comprising in combination with a rotating yarn receiver and a yarn guide traversable lengthwise thereof, a traverse and gain controlling mechanism for the guide; 100 said mechanism embodying an actuator lever having a to and fro stroke, yarn guide holding means and coöperating connecting and governing devices on said lever and between the same and said holding means; said devices comprising a flexible element adapted to move to and fro with said lever, and governing means on said lever active on said flexible element, to move the point of engagement thereof with said flexible element 105 gradually and incrementally outward from the fulcrum of said lever, thereby gradually to increase the traverse, said governing means including a nut having a sheave, a screw to move said nut outward from the 110 fulcrum of the lever, and a second flexible element operatively connected to said sheave and to said actuator lever, the said connecting and governing devices further comprising a member positively connected to said 115 first flexible element and having coöperative relation with said yarn guide holding means.

6. Winding mechanism for forming packages comprising in combination with a rotating yarn receiver and a yarn guide traversable lengthwise thereof, a traverse and gain controlling mechanism for the guide, said mechanism embodying an actuator lever having a to and fro stroke, yarn guide holding means and coöperating connecting and governing devices on said lever and between the same and said holding means; the said devices comprising a first flexible element, governing means on said lever including a sheave to which one end of said flexible element is connected, means to move said sheave outward from the fulcrum of the lever, a second flexible element operatively connected to said sheave and to said actuator lever; the said connecting and governing devices further comprising a second oscillatory, pivoted member positively connected to said first flexible element, and having coöperative relation with said yarn guide holding means.

7. Winding mechanism for forming yarn packages comprising in combination with a rotating yarn receiver, and a yarn guide traversable lengthwise thereof, a traverse and gain controlling mechanism for the guide, said mechanism embodying a member having a to and fro movement, yarn guide holding means, and coöperating and connecting governing devices on said member and between the same and said holding means; the said devices comprising a first flexible element and governing means on said to and fro movable member, said governing means including a sheave to which one end of said flexible element is connected, means to move said sheave outward from the support of said member, and a second flexible element operatively connected to said sheave and to said member, the said connecting and governing devices further comprising means to connect the first flexible element with the yarn guide holding means.

8. Winding mechanism for forming yarn packages comprising in combination with a rotating yarn receiver and a yarn guide traversable lengthwise thereof, a traverse and gain controlling mechanism for the guide, said mechanism embodying a member having a to and fro movement, yarn guide holding means, and coöperating connecting and governing devices on said member and between the same and said holding means; the said devices comprising a first flexible element and governing means on said to and fro movable member, said governing means including a sheave to which one end of said flexible element is connected, means to move said sheave outward from the support of said member, a second sheave fast with the first sheave, a flexible element connected to said second sheave and to said member, the

said connecting and governing devices further comprising means to connect the first flexible element with the yarn guide holding means.

9. In continuously acting yarn package winding mechanism having a traverse and a gain, in combination with the yarn receiver and a yarn guide traversable lengthwise of the receiver; single acting traverse and gain controlling mechanism gradually to increase the traverse throughout the winding operation and gradually to increase the gain throughout the formation of the base of the package, embodying traversable yarn guide holding means and an oscillatory actuator lever having a constant stroke and connecting devices between said holding means and said lever comprising a pivoted member having coöperative relation with said holding means, and a first flexible element positively connected at one end to said pivoted member, a sheave to which the other end of said flexible element is connected, and a second flexible element operatively connected to said sheave and to said actuator lever, said pivoted member and yarn guide holding means being coöperatively arranged, so that fixed incremental rotation of the pivoted member gives an incremental gain to said holding means.

10. Winding mechanism for forming yarn packages comprising in combination with a rotating yarn receiver and a yarn guide traversable lengthwise thereof, a traverse and gain controlling mechanism for the guide, said mechanism embodying a member having a to and fro movement, yarn guide holding means, and coöperating connecting and governing devices on said member and between the same and said holding means; the said devices comprising a first flexible element, and governing means including a sheave to which one end portion of said first flexible element is connected, and a second flexible element operatively connected to said sheave and to said member, the said connecting and governing devices further comprising means to connect the flexible element with the yarn guide holding means.

11. A traverse motion for winding yarn on yarn receivers, comprising in combination rotatable spindles, a ring rail, a rotatable builder element, a builder lever and a ring-rail-rod engaging lever both mounted to oscillate in planes lengthwise of the ring frame, said builder lever having two arms, one adapted to be acted upon by said builder element and the second arm extending upwardly toward the ring rail, a first flexible element having one end fixedly connected to said ring-rail-rod engaging lever, a rotatable sheave carried by said upwardly extending arm of the builder lever and to

which the other end of said flexible element is connected, and a second flexible element operatively connected to said sheave and to the first mentioned arm of the builder lever.

5 12. A traverse motion for winding yarn on yarn receivers, comprising in combination rotatable spindles, a ring rail, a rotatable builder element, a builder lever and a ring-rail-rod engaging lever both mounted 10 to oscillate in planes lengthwise of the ring frame, said builder lever having two arms, one adapted to be acted upon by said builder element and the second arm extending upwardly toward the ring rail, a first flexible element having one end fixedly connected to said ring-rail-rod engaging lever, a sheave carried by said upwardly extending arm of the builder lever and to which the other end of said flexible element is connected, means to move said sheave outwardly 15 along the arm by which it is carried, and a second flexible element having one end operatively connected to said sheave and having the other end fixed to the first mentioned 20 25 arm of the builder lever.

13. A traverse motion for winding yarn on yarn receivers, comprising in combination rotatable spindles, a ring rail, a rotatable builder element, a builder lever and a ring-rail-rod engaging lever both mounted 30 to oscillate in planes lengthwise of the ring frame, said builder lever having two arms, one adapted to be acted upon by said builder element and the second arm extending 35 upwardly toward the ring rail, a first flexible element having one end fixedly connected to said ring-rail-rod engaging lever, a sheave carried by said upwardly extending arm of the builder lever and to which the other end of said flexible element is connected, said sheave being interchangeable 40 with sheaves of other diameters, means to move said sheave outwardly along the arm by which it is carried, a second sheave fast 45 with said first sheave but of larger diameter than and removable from said first sheave, and a second flexible element having one end connected to said second sheave and having its other end fixed to the first mentioned arm of the builder lever.

50 14. Traverse motion for winding yarn on yarn receivers, comprising in combination rotatable spindles, a ring rail, a rotatable builder element, a builder lever and a ring-rail-rod engaging lever both mounted 55 to oscillate in planes lengthwise of the ring frame, said builder lever having two arms, one adapted to be acted upon by said builder lever and the second arm extending upwardly toward the ring rail, a screw shaft 60 carried by said second arm and extending outward from the pivot of the builder lever, a nut upon said screw shaft and having a stud shaft, three sheaves fast upon said

stud shaft, a pair of flexible elements connected to said ring-rail-rod engaging lever and to a pair of said sheaves, and a second flexible element fixedly connected to the third sheave and to the first mentioned arm of the builder lever.

- held in fixed relation to each other and to one of which said first flexible element is connected, means to move both of said members outward from the fulcrum of the lever, 65
 5 a second flexible element connected to said second member and to said actuator lever; the said connecting and governing devices further comprising a second oscillatory, pivoted member positively connected to said 10 first flexible element, and having coöperative relation with said yarn guide holding means.
18. Winding mechanism for forming yarn packages comprising in combination, a rotating yarn receiver and a yarn guide traversable lengthwise thereof, a traverse and gain controlling mechanism for the guide, said mechanism embodying a member having a to and fro movement, yarn guide holding means and coöperating and connecting 15 governing devices between said member and said holding means, said devices including a first flexible element operatively connected to the yarn-guide holding means, traverse and gain-governing means upon said to-and-fro 20 movable member, and to which governing means one end portion of said flexible element is connected, means to move said governing means in a determined path, and a second flexible element operatively connecting 25 said governing means and said to and fro movable member.
19. Winding mechanism for forming yarn packages comprising in combination, a rotating yarn receiver and a yarn guide traversable lengthwise thereof, a traverse and gain controlling mechanism for the guide, said mechanism embodying a member having a to and fro movement, yarn guide holding means and coöperating and connecting governing devices between said member and said holding means, said devices including two 30 flexible elements, one operatively connected to said to and fro movable member and the other to said yarn guide holding means, and intermediate traverse and gain controlling means movable incrementally in a determined path that extends in a general upward direction toward the yarn receiver and to which intermediate means both of said 35 flexible elements are operatively connected.
20. Winding mechanism for forming yarn packages comprising in combination, a rotating yarn receiver and a yarn guide traversable lengthwise thereof, a traverse and gain controlling mechanism for the guide, said mechanism embodying a member having a to and fro movement, yarn guide holding means and coöperating and connecting governing devices between said member and 40 said holding means, said devices including two flexible elements, one operatively connected to said to and fro movable member, and the other to said yarn-guide holding means, and intermediate, rotatable traverse
- and gain-controlling means upon said to-and-fro movable member and bodily movable in a determined path and to which both of said flexible elements are operatively connected. 65
 21. Winding mechanism for forming yarn packages comprising in combination, a rotating yarn receiver and a yarn guide traversable lengthwise thereof, a traverse and gain controlling mechanism for the guide, said mechanism embodying a member having a to and fro movement, yarn guide holding means and coöperating and connecting governing devices between said member and said holding means, said devices including two flexible elements, one operatively connected to said to and fro movable member and the other to said yarn guide holding means, an intermediate rotatable traverse and gain controlling member upon said to-and-fro movable member and to which both of said flexible members are operatively connected, and means to impart bodily, traverse-controlling movement to said rotatable member. 70

 24. Winding mechanism for forming yarn

packages comprising in combination with a rotating yarn receiver and a yarn guide traversable lengthwise thereof, a traverse and gain controlling mechanism for the guide, 5 said mechanism including a member having a to and fro movement, yarn guide holding means and coöperating connecting and governing devices between said member and said holding means, said devices comprising a 10 first flexible element, and traverse and gain governing means upon said to and fro movable member and to which governing means one end portion of said first flexible element is connected, said governing means includ-

ing a member having a movement of rotation, means to move said rotatable member along said to and fro movable member, and a second flexible element operatively connected to said rotatable member and to said to and fro movable member. 15

In testimony whereof, I have signed my name to this specification, in the presence of two subscribing witnesses. 20

CHARLES B. WEBSTER.
